UNITED STATES PATENT OFFICE.

LOUIS G. WILHEMS, OF HARTFORD CITY, INDIANA, ASSIGNOR OF ONE-HALF TO CHARLES GWINNUP, OF MUNCIE, INDIANA.

SIGN.

No. 861,689.

Specification of Letters Patent.

Patented July 30, 1907.

Application filed December 8, 1906. Serial No. 346,845.

To all whom it may concern:

Be it known that I, LOUIS G. WILHEMS, a citizen of the United States, and a resident of Hartford City, in the county of Blackford and State of Indiana, have invented a new and useful Sign, of which the following is a specification.

My invention relates to improvements in signs and has especial reference to signs wherein electric light is the medium of illumination.

10 One of the faults of electric signs as they are at present devised, is that in the delineation of the letters composing the sign a great number of incandescent lamps are required, and for any sizes other than those having letters of very large dimensions the effect produced in the illumination of the letters is so dazzling as to render the view separately of the letters quite indistinct, especially when viewed from a distance. When it has been attempted to illuminate letters built up, with a number of electric lamps less than the number necessary in themselves to complete the outline of the letter, the letters are only illuminated partially, and in the scattered position of the lamps, the sign is not easily read except from a short distance, moreover by reason of the great number of lamps needed in the illumination of such signs they are very expensive to operate, and further, the electric lamps being arranged on the exterior of the device they are subject to breakage, and frequent renewals of the same are necessary to keep the sign in working order.

20

30 The object of my invention is to provide a sign which will be effective as a day-sign, and, by the novel construction and arrangement of parts to be described hereinafter, to obtain a sign which may be read at night with great distinctness, from a distance great or small. Also to provide such a sign which will be economical of manufacture, easy to operate and which will be durable and not liable to get out of repair. These objects are accomplished by the construction, arrangement and combination of parts described in the 40 annexed specification, pointed out in the appended claims and illustrated in the accompanying drawings, in which—

Figure 1 is a front perspective view of my improved sign complete; Fig. 2. is a vertical longitudinal sectional view taken on the line 2—2 Fig. 1 and Fig. 4 is a vertical longitudinal sectional view taken on the line 4—4 Fig. 1. Fig. 3 is a transverse sectional view taken on the line 3—3 Fig. 1. Fig. 5 shows my improved sign as viewed from below.

50 Similar characters of reference refer to corresponding parts throughout the several views.

1 designates the walls, made of thin sheets, preferably of sheet metal; 2 is the top and 3 the ends of my improved sign, made of wood or sheet metal of suitable thickness or gage, suitably secured together in the

form of a box, as shown in Fig. 1. The bead or molding 4 is provided about the edges of the walls to effect a neat finish.

5 designates a pair of bottom rails secured along the lower sides of the box whereby it is stiffened and a casement is provided for the hinged doors 6.

In the walls are delineated by perforations, as plainly shown in Fig. 1 the letters and the ornamentation desired to be displayed. To render these perforations luminous from the light given by the electric lamps 65 within the box I provide an interior lining 7 for the walls consisting of sheet glass of proper thickness, rendered translucent or semi-translucent and having the color I desire to appear in the letters or ornamental symbols in the sign. This lining may be of frosted or ground glass, or it may be rendered of the proper degree of translucency by painting it. To accomplish the maximum luminosity of my improved sign with a given number of lamps, the entire interior of the sign-box is provided with a solid white coating. By this mode of utilizing the light afforded by the electric lamps a minimum quantity of its strength is absorbed and great effectiveness is obtained, the perforations being rendered exceedingly luminous and sharply defined, thereby making a brilliant, clean-cut and distinct display of the sign, without dazzling or confusion. Moreover the very effective luminosity so accomplished, is so obtained with the expenditure of much less current, and words so delineated may be read much more easily and for a distance much greater than the 85 electrically illuminated signs as now constructed. About the said perforations the letters may be outlined and painted as in an ordinary sign thus adding effectiveness and utility to the device as a day-sign.

Rigidly secured along the lower inner portion of the 90 walls, by soldering or riveting, are the rabbeted strips 8 in the rabbet 9 of which the lower edge of the glass lining is inserted.

10 designates suitably formed clips properly placed with reference to the strips 8 and loosely supported on threaded studs secured in the wall and provided with the thumb nuts 11. By this arrangement, as will be readily seen, the lining for the letters may be easily placed and secured in position.

I have shown the lining composed of a plurality of 100 sheet glasses, which is preferable to making the lining of a single piece of glass, except in signs of small dimensions. These separate sheets of glass may be provided in sets of different colors so the display of the letters and characters of the sign may be varied and 105 changed at pleasure. Another purpose in making this lining in separate sections is that if for any cause breakage of the glass might occur, probably only a part of the lining would be destroyed and the replacement thereof would be inexpensive.

Extending the length of the box and slidingly secured between the two pairs of guides 12, is the vertically disposed frame 13 adapted to support the electric lamps and the wiring therefor. I have shown the 5 frame as supporting the two lamps 14 which are sufficiently effective to illuminate a sign of the ordinary form and medium size as illustrated herein. It is intended that any required or desired number of lamps 10 may be supported by this frame and that they may be arranged at divers locations therein so as to suitably and properly illuminate a sign of any dimensions and having any amount of lettering and ornamentation.

15 designates a pair of spring clips secured to the under side of the top of the box their lower ends flaring apart. In inserting the frame 13 into position in the box it is pushed upwardly in the guides therefor, and as it passes the spring clips 15 they are strained apart, permitting the frame to pass and they immediately grasp and retain it in proper position, as shown 20 in Fig. 4. In the larger signs wherein the frame will necessarily be of greater weight additional pairs of spring clips are provided.

By the construction of my improved sign as described, the electric lamps are at all times protected 25 and shielded from the elements and breakage of them by storms or flying objects is prevented. A comparatively small number of lamps is required to effectively illuminate the most elaborate sign, either on two walls thereof or simply one. Also the removable frame renders easy the arrangement, installation, and rearrangement 30 of the lamps and the rearrangement or repairing of the wiring.

16 designates a suitable socket or connection located at a proper place on the end of the frame, so the plug 35 by which the current is introduced into the lamps may be readily inserted and the connection made through the small door 17 of the box.

In the bottom edge of the frame are provided the staples 18 which are engaged by the hooks 19 attached to the doors 6. These doors, as plainly shown in Fig. 5 40 are so hinged at the ends of the box, that when they are released from their normal closed position fastened to the frame 13, they swing downwardly and completely out of the way and permit of free and ready access to the interior of the box. 45

20 designates eye-clips secured to the upper portion of my device whereby it may receive the connections of suitable supporting means.

What I claim as my invention and desire to secure by Letters Patent, is

1. An electrically illuminated sign comprising a box having all of its sides opaque, the letters and characters composing the sign being delineated by perforations in the walls of the box the bottom thereof being hinged so as to swing completely open, there being support plates 55 secured to the box and an opening in the end of the box, grooved or rabbed strips on the inner-faces of the walls and loose clips secured to the walls whereby a lining may be detachably retained against the said walls, a frame 60 wherein is supported electric lamps disposed in the said box retained in guides and, detachably held in position by clamps secured to the interior of the box there being fastenings on the bottom of said frame for the attachment of the hinged doors.

2. In a sign, the combination with the box therefor 65 having a hinged bottom, there being in its walls delineated by perforations the letters and characters thereof and translucent lining secured to the inner faces of said walls, of a removable frame carrying electric lamps, slidingly seated in guides at the ends of the box and adapted to be 70 slid into position and retained in the box by yieldable means secured to the box, said frame having means secured to its bottom whereby the hinged bottom of the box may be secured and the box thereby closed.

In testimony whereof I have signed my name to this 75 specification in the presence of two subscribing witnesses.

LOUIS G. WILIEMS.
